UNITED STATES PATENT OFFICE.

ARTHUR H. SYMONS AND GEORGE E. CONKLIN, OF KANSAS CITY, KANSAS; SAID CONKLIN ASSIGNOR TO SAID SYMONS.

CLAMP FOR CONCRETE-FORMS.

1,036,025.

Specification of Letters Patent. Patented Aug. 20, 1912.

Application filed December 8, 1910. Serial No. 596,218.

To all whom it may concern:

Be it known that we, ARTHUR H. SYMONS and GEORGE E. CONKLIN, citizens of the United States, residing at Kansas City, in

5 the county of Wyandotte and State of Kansas, have invented certain new and useful Improvements in Clamps for Concrete-Forms; and we do declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

Our invention relates to an improved clamp for concrete forms, more particularly forms for constructing columns, or the like; the principal object of the invention being 20 to provide means for holding the boards of the form close together while the material is being poured and while such material is becoming hardened or "set". In constructing forms of this character it has been customary to nail cross pieces or clamps to the 25 vertical form boards and place wedges between the clamps and the body of the form, in order to close the cracks between the boards. With this construction, the material of which a form is made, may be used 30 a limited number of times, and after being so used is practically worthless for any other purpose, as it is usually split from being repeatedly nailed together and torn apart.

35 Our improved device is adapted for obviating these disadvantages by providing a metal clamp which may close the form tightly together and hold same in position during the pouring and setting process, and 40 which may be easily and quickly removed without damaging the material of which the form is constructed; the improved details of structure of our improvement being illustrated in the accompanying drawings, in 45 which:—

Figure I is a perspective view of a column form, to which one of our improved clamps is applied. Fig. II is a detail view of one of the clamp units. Fig. III is an enlarged detail plan view of the overlying arms of the separate clamp units, showing the application of the corner bracket and the tightening lever. Fig. IV is a detail perspective of a corner bracket which forms a 55 part of our improved clamp. Fig. V is a

similar view of the reverse side of same. Fig. VI is a view of the locking pin. Fig. VII is a perspective view of the tightening lever.

Referring more in detail to the parts:— 60 1 designates a column form which is preferably constructed of boards arranged on end and in edge contact, the form here shown being square, although our improved clamp may be adapted for use with forms of other 65 cross section.

2 designates the clamp unit which, in this construction, are two in number and formed of metal arms 3, the arms being preferably formed of strap metal, and pivotally connected at one end by the pins 4, the free ends of the arms being provided with a number of apertures 5 for a purpose presently described. In applying the units to the column form, the arm members are placed 70 on opposite corners of the form, so that, in the strap construction, the edges of the straps lie close against the sides of the form, the apertured portions overlying each other, as shown in Figs. I and III. 80

6 designates corner brackets, having slots 6' in their respective members, the slots in opposite members being arranged in parallel planes and spaced according to the width of the strap with which they are to be used, 85 in order that, when the strap units have been positioned, the brackets may be placed thereover, so that said straps may lie flat upon each other and project through the bracket slots without jamming. Brackets 6 90 are preferably formed of cast metal and provided with strengthening ribs 6'' at their inner corners (Fig. III), and with grooves 7, at each side of the slots 6'.

8 designates a lever which is formed of a 95 piece of strap metal having a cam end 9, and a cut out portion 10 in one edge. Fixed in the sides of the cam head are pins 11, which project therefrom and are adapted to take into the main strap apertures when the 100 parts are assembled.

12 designates pins which are adapted to fit within the strap apertures 5 and have heads that may either be supported on the face of the strap or on the edge of the 105 bracket 6 when the parts are assembled.

In using our improved clamp, the column form is assembled in the usual manner and a pair of the clamps applied to opposite corners thereof, so that their apertured ends 110

overlie each other. With the clamps placed on the form, the corner brackets are positioned over the crossed ends of the clamp straps by sliding the slotted portions of the bracket over the ends of the straps. The lever is then applied to one of the straps by projecting its pin into one of the strap apertures, adjacent to the bracket, and moving the cam head into the groove over the strap slot. By prying the lever back, the cam head will bear against the bracket and pull the arm 3 through the slot, binding one arm tightly against the form and pulling the opposite arm tightly against the opposite side of the form. By providing the cut out portion 10 in the edge of the lever near the cam head, a space is left through which a pin may be projected into one of the arm apertures, whereas if the lever were straight, the proper aperture might be covered so that the pin could not be dropped into place. As soon as one strap has been tightened, a pin is dropped into the aperture, closest to the bracket, in order to hold the clamp in its tightened position. The other straps are then tightened in like manner; the grooved portions of the bracket holding the cam head of the lever, so that it will not be displaced vertically under the tightening tension.

It is apparent that a number of clamps may be applied to a single form and that when either applying the clamp or removing same, the material of which the form is constructed will not be destroyed or injured, and that the clamps may be used repeatedly without injury to themselves or to the forms to which they are applied.

Having thus described our invention, what we claim as new therein and desire to 40 secure by Letters-Patent is:—

1. A clamp for concrete forms comprising arm members arranged in sets, each set having its members pivotally connected at one end, brackets, having members extending 45 at right angles to each other, the said members provided with slots communicating with their free ends, the slot in one of said members disposed in the upper portion thereof and the slot in the other member 50 disposed in the lower portion of said member, the said slots being adapted to receive said arm members through their free ends and provide means whereby the said arm members will overlap within said bracket. 55

2. A clamp for concrete forms, comprising arm members arranged in sets, each set having its members pivotally connected at one end, brackets having members disposed at right angles to each other, said members provided with slots communicating with their free ends, the slot of one of the members being disposed in the upper portion of said member and the slot of the other member disposed in the lower portion thereof, 60 whereby the said arms will overlap within the angle of said bracket, and ribs formed integral with said angle members and engaging the corners of said concrete forms. 65

In testimony whereof we affix our signatures in presence of two witnesses. 70

ARTHUR H. SYMONS.
GEORGE E. CONKLIN.
